US0D1110423S

(12) United States Design Patent (10) Patent No.: US D1,110,423 S
(45) Date of Patent: * Jan. 27, 2026

(54) BUBBLE MACHINE

(71) Applicant: Dakai Chen, Shantou (CN)

(72) Inventor: Dakai Chen, Shantou (CN)

() Term: 15 Years

(21) Appl. No.: 29/975,708

(22) Filed: Dec. 1, 2024

(30) Foreign Application Priority Data

Oct. 11, 2024 (CN) 202430640240.2

(51) LOC (15) Cl. 21-01

(52) U.S. Cl.

USPC D21/401

(58) Field of Classification Search

USPC D21/398, 401, 407, 473, 474, 572, 597

CPC A63H 33/28; A63H 33/00; A63H 29/22;

A63H 23/10

(57) CLAIM

The ornamental design for a bubble machine, as shown and described.

DESCRIPTION

FIG. 1 is a first perspective view of a bubble machine showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the bubble machine that form no part of the claimed design.

1 Claim, 8 Drawing Sheets
